(No Model.)

J. Q. C. SEARLE.
CAR HEATING APPARATUS.

No. 461,282.

Patented Oct. 13, 1891.

UNITED STATES PATENT OFFICE.

JOHN Q. C. SEARLE, OF CHICAGO, ILLINOIS.

CAR-HEATING APPARATUS.

SPECIFICATION forming part of Letters Patent No. 461,282, dated October 13, 1891.

Application filed March 4, 1891. Serial No. 383,755. (No model.)

To all whom it may concern:

Be it known that I, JOHN Q. C. SEARLE, a citizen of the United States, residing at Chicago, in the county of Cook and State of Illinois, have invented new and useful Improvements in Car-Heating Apparatus, of which the following is a specification.

This invention relates to improvements in that class of hot-water warming apparatus shown and described in my patents, No. 311,534, February 3, 1885, and No. 340,825, April 27, 1886, in which the water is heated in a single coil and made to circulate through separate and distinct lines of pipe on each side of the car and requiring but one expansion-chamber for the heating apparatus in each car; but owing to the increased size and length of railway-cars as now constructed it is found desirable that increased heating capacity be provided and more hot water supplied to the circulating-pipes without enlarging the heater.

My present invention consists in providing a hot-water warming apparatus comprising a heater, two separate and distinct heating and circulating passages, a combined water-uniting and expansion chamber, a water-dividing chamber, a pipe that connects the water-uniting chamber and water-dividing fitting, two separate descending pipes, two separate sets of circulating-pipes that heat the car, and two return-pipes for returning the cooled water to the heating and circulating passages from which it started, by which I am enabled to increase the heating capacity and supply more hot water to the circulating-pipes without enlarging the heater. The return-pipes may be provided with one or more cocks or valves, whereby an even circulation and an even temperature can be effected on each side of the car, which on a cold day with a strong wind blowing against one side of a train of cars has heretofore made it impossible to warm that side of the car.

The annexed drawing is a perspective of a hot-water warming apparatus with a heater in section, showing the combination of parts whereby the water that is heated in two separate and distinct heating and circulating passages is conducted to the circulating-pipes

that heat each side of the car, and afterward by two return-pipes the cooled water is returned to the separate heating and circulating passages from which it started.

The numeral 1 designates a heater provided with a heating-coil 2 and a separate heating and circulating passage 3, though any other approved form of heating device having two separate heating and circulating passages will answer to heat the water that warms the car. After the water has been properly heated it is conducted through pipes 4 and 5, a combined water-uniting and expansion chamber 6, pipe 8, water-dividing fitting 15, and descending pipes 9 and 12 to the circulating-pipes 10 and 13, that heat each side of the car separately, and by the pipes 11 and 14 the cooled water is returned to the separate heating and circulating passages from which it started.

It further consists in providing means whereby an even circulation and an even temperature is secured on each side of the car. To obtain this result I place in the pipes 11 and 14 a cock or valve, as 19 and 20, by means of which the circulation may be regulated.

Should the water circulate faster on one side than on the other, one of the valves may be partly closed, and the circulation thereby retarded enough to cause both flows to reach the heater in about the same time.

The expansion-chamber 6 is provided with a safety-valve 21 to prevent explosion and a funnel-cock 22 for supplying any loss of water to the entire apparatus at one point, as all parts of the apparatus communicate with said expansion-chamber 6. The necessity of having a separate expansion-chamber for each side of the car is avoided and the consequent increased attention of the train-men to see that each side of the apparatus is safe and in proper condition for use is very much lessened.

The advantages of a hot-water warming apparatus having two separate heating and circulating passages, a combined water-uniting and expansion chamber, a water-dividing fitting, and two separate sets of heating and circulating pipes will be obvious, as thereby but one water-uniting and expansion chamber and

one water-dividing fitting is required, and the construction and operation of the apparatus are made very simple.

I do not herein broadly claim the combination of a furnace, a plurality of independent liquid-heating passages therein, a plurality of independent radiators communicating with the liquid-heating passages, and a temperature - equalizing chamber, pipe, or passage 5 communicating with the upper ends of the said liquid-heating passages and with the radiators, as such constitutes the subject-matter 10 of my application for Letters Patent filed October 9, 1890, Serial No. 367,565.

Having thus described my present invention, what I claim herein as new, and desire to 15 secure by Letters Patent, is—

1. The combination, in a hot-water warming apparatus, of a heater, two separate and 20 distinct heating and circulating passages, a combined water-uniting and expansion chamber 6, the pipes 4 and 5, that connect said heating and circulating passages with said water-uniting and expansion chamber, the water-dividing fitting 15, the pipe 8, that connects said 25 water-uniting and expansion chamber with said water-dividing fitting, the circulating-pipes 10 and 13, that heat the car, the pipes 9 and 12, that connect said circulating-pipes 30 with said water-dividing fitting, and the re-

turn-pipes 11 and 14, that return the cooled water to the separate heating and circulating passages from which it started.

2. The combination, in a hot-water warming apparatus, of a heater, two separate and 35 distinct heating and circulating passages, a combined water-uniting and expansion chamber 6, the pipes 4 and 5, that connect said heating and circulating passages with said water-uniting and expansion chamber, the 40 water-dividing fitting 15, the pipe 8, that connects said water-uniting and expansion chamber with said water-dividing fitting, the circulating-pipes 10 and 13, that heat the car, the pipes 9 and 12, that connect said circulating-pipes 45 with said water-dividing fitting, and the return-pipes 11 and 14, that return the cooled water to the separate heating and circulating passages from which it started, provided with one or more cocks, whereby an 50 even circulation and an even temperature may be produced on each side of the car.

In testimony whereof I have hereunto set my hand and affixed my seal in presence of two subscribing witnesses.

JOHN Q. C. SEARLE. [L. S.]
